(57) **CLAIM**

The ornamental design for a light fiber connection interface, as shown and described.

DESCRIPTION

FIG. 1 is a perspective view of a first embodiment of a light fiber connection interface;

FIG. 2 is a front view of the light fiber connection interface of FIG. 1;

FIG. 3 is a rear view of the light fiber connection interface of FIG. 1;

FIG. 4 is a left side view of the light fiber connection interface of FIG. 1;

FIG. 5 is a right side view of the light fiber connection interface of FIG. 1;

FIG. 6 is a top view of the light fiber connection interface of FIG. 1;

FIG. 7 is a bottom view of the light fiber connection interface of FIG. 1;

FIG. 8 is an exploded view of the light fiber connection interface of FIG. 1;

FIG. 9 is a cross-sectional view of the light fiber connection interface of FIG. 1, taken along 9-9;

FIG. 10 is a perspective view of a second embodiment of a light fiber connection interface;

FIG. 11 is a front view of the light fiber connection interface of FIG. 10;

FIG. 12 is a rear view of the light fiber connection interface of FIG. 10;

FIG. 13 is a left side view of the light fiber connection interface of FIG. 10;

FIG. 14 is a right side view of the light fiber connection interface of FIG. 10;

FIG. 15 is a top view of the light fiber connection interface of FIG. 10;

FIG. 16 is a bottom view of the light fiber connection interface of FIG. 10;

FIG. 17 is an exploded view of the light fiber connection interface of FIG. 10; and,

FIG. 18 is a cross-sectional view of the light fiber connection interface of FIG. 10, taken along 18-18.

The broken lines illustrate portions of the light fiber connection interface that form no part of the claimed design.
